UNITED STATES PATENT OFFICE.

THEOPHILUS ARNDT, OF FLORIN, ASSIGNOR OF ONE-HALF TO HENRY H. HEISE, OF COLUMBIA, PENNSYLVANIA.

AUTOMATIC RAILWAY-SIGNAL.

SPECIFICATION forming part of Letters Patent No. 289,953, dated December 11, 1882.

Application filed June 11, 1883. (No model.)

To all whom it may concern:

Be it known that I, THEOPHILUS ARNDT, a citizen of the United States, residing at Florin, in the county of Lancaster and State 5 of Pennsylvania, have invented a new and useful Improvement in Automatic Railway-Signals; and I do hereby declare that the following is a full, clear, and exact description of the same, reference being had to letters 10 marked on the accompanying drawings, in which—

Figure 1 is a side view of a locomotive with my improvements. Fig. 2 is a rear elevation of my improvement, partly in section, and 15 Fig. 3 is a detail view. Fig. 4 is a detailed sectional view on line $y-y$ of Fig. 2.

My invention relates to improvements in automatic railway-signals; and it consists in the peculiar construction and arrangement of 20 the parts, as hereinafter more fully set forth, and pointed out in the claims.

In the accompanying drawings, a a represent the two rails of a railway-track, and b represents a rail sloped at its ends and arranged 25 near one of the rails of the track and above it, so as to be just cleared by the cow-catcher, and preferably between the rails, as shown in the drawings.

c represents a locomotive of the usual form, 30 provided with a steam-drum, d , having a steam-whistle, e , attached thereto, the latter being secured to a vertical spring-rod, h , bent downward, preferably at its upper end, and secured to one end of the inner one of the 35 cranks i of the horizontal double-crank shaft k . The double-crank shaft k is journaled in the bracket l , fixed to the frame of the cab. The outer crank, i , is provided at its end with a threaded vertical rod, m , which passes 40 through a hole, n , in the outer end of the stay-plate or bracket o , secured to the frame of the cab, and thence passes near its lower end through the right-angular projection p , secured to the upper end of the plate q , to the lower end of which the wheel r is secured, which wheel, in the movement of the locomotive, is adapted to run on the sloped rail b , inside one of the rails, and operate the steam-whistle. 45

This construction is extremely simple, involving but few parts, and is much cheaper than

the ordinary construction. The plate q , carrying the wheel r , rises and falls in passing over the sloped rail b in a recess, s , made in one side of the plate t .

t represents a plate secured to the frame of the locomotive over the plate q , to hold it in place, and at the same time to permit the plate q to slide up and down freely in the recess s .

u represents a thimble retained upon the lower end of the vertical rod m by a nut, v , below the angular projection p . The upper end of the thimble u is provided with a head, which rests upon the angular projection p of the sliding plate q . The function of the thimble u is to prevent binding of the rod m in its movements up and down. The rod m is threaded and provided with nuts a' above and below the bracket o , and having jam-nuts a^2 , to hold the adjusting-nuts a' in any desired position. The functions of the nuts a' a^2 on the rod m are to adjust the length of rod m and the tension of spring b' . A spiral spring, b' , encircles the lower end of the rod m and lies between the head of the thimble and the nut a' for adjusting the tension of the spring. When desired, the rod m may be raised high enough by adjusting the upper nut a' , to avoid operating the whistle by the rise and fall of the plate q and wheel r as they pass over rail b . 75

What I claim as my invention is—

1. The combination, with the sloped rail b , elevated above the track, and steam-whistle e , of the double-crank shaft i i k , bracket o , 80 threaded rod m , spiral spring b' , thimble u , nuts a' , and plate q , carrying the wheel r , substantially as described, and for the purpose set forth.

2. The combination, with the steam-whistle e , connected with the double-crank shaft i i k , of the stay-plate o , threaded rod m , carrying spiral spring b' , thimble u , plate q , having wheel r at its lower end, and plate t , substantially as described, and for the purpose set forth. 90

THEOPHILUS ARNDT.
